(57) **CLAIM**

The ornamental design for an internal snap member, as shown.

DESCRIPTION

FIG. 1 is a front, top and right-side perspective view of an internal snap member showing our new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof; and,

FIG. 7 is a right side view thereof.

1 Claim, 7 Drawing Sheets(56)
